UNITED STATES PATENT OFFICE.

ERWIN ALEXANDER WECK, OF DOLAU, REUB, GERMANY.

MECHANICAL STOKER.

Application filed September 18, 1922. Serial No. 588,016.

To all whom it may concern:

Be it known that I, ERWIN ALEXANDER WECK, a citizen of the German Republic, residing at Dolau, Reub, Germany, have 5 invented certain new and useful Improvements in Mechanical Stokers, of which the following is a specification.

The well known grate charging apparatus with swinging shovel and with a wedge-shaped nose of the shovel for spreading out the coal in fan-shape over the grate when the same is being thrown upon the grate with varying strength, possesses the inconvenience that the coal is generally not 10 spread out wide enough at the front end of the grate while at the rear end of the grate the spreading out is broad enough or even too broad. Consequently the coal accumulates at the front end of the grate at the 15 middle but not at the sides. This inconvenience is avoided by the invention.

According to the invention the two-armed curved cam which is pivotally mounted upon the driving wheel for the shovel and 20 whose position is periodically altered for altering the length of throw with the aid of convenient means, co-operates with a fixed roller in such a manner that the rear end of the lever is lifted by the roller shortly before 25 it releases the tappet of the shovel. Consequently the shovel, at the short throw, is slightly pulled back from the coal which has dropped in front of it, so that it strikes into the coal from a certain distance. The 30 rebounding stroke which is thus produced has the effect that, at the short throw, the coal is spread out in lateral direction.

As at long throws the above mentioned 35 roller does not act upon the cam the shovel is in direct contact with the coal so that the rebounding effect does not take place and the coal is consequently not spread very much.

The object of the invention is shown by 40 way of example on the accompanying drawing, wherein:

Fig. 1 is a vertical section through the throwing box of a grate charging apparatus, the section plane being situated in the longitudinal axis of the grate.

Fig. 2 shows a part of the throwing box in front elevation the driving mechanism being shown in cross section.

Fig. 3 is a section on the line 3-3 of 45 Fig. 2, the driving disk which supports the pivoted lever being omitted. The cam is

adjusted for wide throw. The tappet is at the middle position with regard to the cam.

Fig. 4 is a view similar to Fig. 3, the parts 50 being shown in the position shortly before the release of the tappet.

Fig. 5 is a view similar to Fig. 3, the pivoted cam being adjusted for short throw and the tappet being at the middle position with regard to the pivoted cam.

Fig. 6 is a similar view to Fig. 5, the tappet being shown in the position just before its release.

The tappet *b* rigidly fixed upon the axle 70 *c* serves for operating the shovel *d* which is adapted to swing around the axle *c*, and the outer edge of which moves in contact with the curved supporting plate *p*. This tappet *b* is lifted, against the action of a 75 spring *k* by the cam *a*. As soon as the tappet *b* is released by cam *a* the spring makes the tappet *b* and with it the shovel *d* swing back so that the shovel *d* throws upon the grate the coal which has dropped in front 80 of it.

The cam *a* is pivotally mounted upon the driving disk *i* by means of bolt *e*. The driving disk *i* has teeth at its circumference by means of which it is revolved uniformly.

Upon the shaft *l* of the driving disk *i* or upon the hub of said driving disk a cam disk *f* is revolvably mounted. The cams *g* of this disk *f* are adjustable in radial slots so that the distance of each cam from the 90 shaft *l* can be adjusted. As will be seen from Figure 2 the cams *g* have shanks extending through the radial slots and nuts are provided on the protruding ends of the shanks thus allowing the cams to be positionally adjusted in the slots. After each throw of the shovel *d* another cam *g* gets under the end of the cam *a* (the left end upon the drawing) so that the length of throw is 95 altered.

The displacement of the cams *g* with regard to the cam *a* is effected by means of the following mechanism:

On the disk *i* a cam *m* is arranged which at each revolution of disk *i*, after each stroke 105 of the shovel *d* pushes to the right a roller *q* which is mounted on the sleeve *n* adapted to be displaced on axle *s* against the action of spring *r*. The sleeve *n* carries a bolt *o* engaging with an annular groove of disk *f*. The disk *f* participates therefore in the displacement of the roller *q* and the bush *n*.

From the displacement of disk *f* results that the bolts *t* fixed on disk *i* disengage from notches of the disk *f* so that this disk no longer participates in the rotation of disk *i*.
 5 Any accidental rotation of disk *f* is prevented by a locking tooth *u* fixed on the machine frame coming in gear with teeth *v* when the disk is in the extreme right hand position, said teeth *v* being arranged on the right hand face of disk *f*.

After disk *i* has executed one eighth of a revolution without drawing along disk *f*, so that another cam *g* has come under the left end of the lever *a*, the cam *m* leaves the roller *q* so that the bush *n*, and with it the disk *f*, is again shifted to the left by the action of spring *r* and the bolts *t* come again in engagement with the notches of disk *f*. This disk *f* participates thus again in the 15 rotation of disk *i* until the tappet *b* with the shovel has been raised by the cam *a* and released, thus executing a stroke. The same procedure is repeated again. This arrangement is shown and described in German 20 patent 333,022 of 1921. The farther the cam which is going to act upon the lever is away from the center of the disk *f* the greater will be the stroke of the tappet *b* and consequently the oscillation of the shovel *d*. Figs. 3 and 4 show a cam, which is 25 comparatively far distant from the center of the cam disk, acting upon the cam *a*, the tappet being shown in Fig. 4 in the position ready for release. The corresponding position of the shovel *d* is indicated in Figs. 3 to 30 6 in dash lines.

After the shovel *d* has been slowly lifted and its spring put under tension by the front end of lever *a* the coal drops in 40 the direction of the arrow in front of the shovel. The cam being in the position shown in Figs. 3 and 4 the tension of the spring of the shovel *d* is not increased any more but rather slightly decreased after the 45 coal has dropped so that at the stroke of the shovel which is produced by the action of the spring as soon as it is released by the cam *a*, the coal lies directly in front of the shovel and is consequently thrown far but 50 but not much spread out.

A roller *h* arranged upon the casing *m* is so adjusted that, if the cam *a* is adjusted for large throw, that is if the rear end of the cam *a* extends comparatively far towards the outer side, the front end of the cam *a* being consequently pressed inward, the roller *h* does not come in contact with the cam *a* at the rotation of the driving wheel *i*. If however the cam *a* is adjusted for short 60 throw as shown in Figs. 5 and 6, the front end of the lever *a* comes in contact with the roller *h* at the rotation of the driving wheel *i*, whereby, shortly before the tappet *b* drops off the lever, the rear end of said lever is swung outward and the tension of 65

the spring of the shovel *d* is increased. The shovel *d* moves therefore away from the coal so that if the lever *a* releases the tappet *b* the shovel rebounds into the coal which is not thrown far but strewn broadly.

The device has therefore at a short throw 70 a rebounding action whereby the coal is strewn broadly this strewing being reduced with the increasing length of throw. The farther the coal is thrown the more the rebounding effect decreases and the closer 75 the shovel remains to the coal. The improved apparatus therefore permits the distribution of the coal uniformly over the entire length and breadth of the grate.

I claim:—

1. In a mechanical stoker of the oscillating spreader type, a spreader mounted to oscillate, means for varying the retractive movement of said spreader for controlling 80 the length of the throw, means for imparting an impelling movement to said spreader, and means for imparting a sudden supplemental retractive movement to said spreader immediately before its discharge movement. 85

2. In a mechanical stoker of the oscillating spreader type, a spreader mounted to oscillate, means for imparting a series of retractive movements of progressively varying extent to said spreader for varying the 90 length of the throw, means for imparting an impelling movement to said spreader, and means for imparting a sudden supplemental retractive movement to said spreader immediately before its discharge movement, 95 the extent of said supplemental retractive movement decreasing as the length of the throw increases. 100

3. A mechanical stoker comprising a supporting plate for a fuel charge, a shovel adapted to oscillate in substantial contact with said plate for discharging the fuel therefrom, an oscillatable axle for supporting said shovel, a tappet arm on said axle, a power-storing device for imparting an impelling movement to said shovel, a rotating drive wheel, a cam element on said drive wheel for cooperating with said tappet arm to swing said shovel into load position against the action of said power-storing device, means for adjusting said cam element for causing a variable oscillation of said shovel, and means for imparting a sudden supplemental retracting movement to said shovel prior to the release of said tappet arm from said cam element when said cam element is adjusted for imparting a relatively small oscillatory movement to said shovel. 115

4. A mechanical stoker comprising a supporting plate for a fuel charge, a shovel adapted to oscillate in substantial contact with said plate for discharging the fuel therefrom, an oscillatable axle for supporting said shovel, a tappet arm on said axle, 120

- a power-storing device for imparting an impelling movement to said shovel, a rotating drive wheel, a cam element pivotally mounted on said drive wheel for cooperating with said tappet arm, means for variably positioning said cam element around its pivotal point for retracting said shovel to a variable extent against the action of said power-storing device, and means for rocking said cam element prior to the release of said tappet arm therefrom for imparting a sudden supplemental movement to said shovel.
5. A mechanical stoker comprising a supporting plate for a fuel charge, a shovel adapted to oscillate in substantial contact with said plate for discharging the fuel therefrom, an oscillatable axle for supporting said shovel, a tappet arm on said axle,

a power-storing device for imparting an impelling movement to said shovel, a rotating drive wheel, a cam element pivotally mounted on said drive wheel for cooperating with said tappet arm, means for variably positioning said cam element around its pivotal point for retracting said shovel to a variable extent against the action of said power-storing device, and a fixed abutment for contacting with said cam element and imparting a rocking movement thereto prior to the release of said tappet arm therefrom for imparting a sudden supplemental retractive movement to said shovel.

The foregoing specification signed at Dolau, Reub, Germany, this 9th day of August, 1922.

ERWIN ALEXANDER WECK.

- a power-storing device for imparting an impelling movement to said shovel, a rotating drive wheel, a cam element pivotally mounted on said drive wheel for cooperating with said tappet arm, means for variably positioning said cam element around its pivotal point for retracting said shovel to a variable extent against the action of said power-storing device, and means for rocking said cam element prior to the release of said tappet arm therefrom for imparting a sudden supplemental movement to said shovel.
5. A mechanical stoker comprising a supporting plate for a fuel charge, a shovel adapted to oscillate in substantial contact with said plate for discharging the fuel therefrom, an oscillatable axle for supporting said shovel, a tappet arm on said axle,
- a power-storing device for imparting an impelling movement to said shovel, a rotating drive wheel, a cam element pivotally mounted on said drive wheel for cooperating with said tappet arm, means for variably positioning said cam element around its pivotal point for retracting said shovel to a variable extent against the action of said power-storing device, and a fixed abutment for contacting with said cam element and imparting a rocking movement thereto prior to the release of said tappet arm therefrom for imparting a sudden supplemental retractive movement to said shovel.
- 10 The foregoing specification signed at Dolau, Reub, Germany, this 9th day of August, 1922.
- 15 ERWIN ALEXANDER WECK.

Certificate of Correction.

It is hereby certified that in Letters Patent No. 1,566,456, granted December 22, 1925, upon the application of Erwin Alexander Weck, of Dolau, Reub, Germany, for an improvement in "Mechanical Stokers," an error appears in the printed specification requiring correction as follows: Page 3, line 12, claim 4, after the word "supplemental" insert the word *retractive*; and that the said Letters Patent should be read with this correction therein that the same may conform to the record of the case in the Patent Office.

Signed and sealed this 2d day of February, A. D. 1926.
